PLANE-LANDING CATAPULT

Maurice F. Jones, Pittsburgh, Pa., assignor to
Westinghouse Electric Corporation, East Pitts-
burgh, Pa., a corporation of Pennsylvania

Application March 8, 1947, Serial No. 733,286

13 Claims. (Cl. 244—63)

1

My invention relates to electric linear-motor catapults, and particularly to control-means for utilizing such catapults for making assisted plane-landings, to reduce the length of the landing-run of an airplane which is landing at a landing-field.

The general type of catapult-equipment to which my invention is related is described and claimed in a patent of Frank B. Powers, 2,404,984, granted July 30, 1946, and also described and claimed in a patent of R. C. Jones, 2,412,514, granted December 10, 1946, a patent of R. C. Jones and myself, 2,412,515, granted December 10, 1946, my Patent 2,428,570, granted October 7, 1947, an application of R. C. Jones, Serial No. 537,515, filed May 26, 1944, my application Serial No. 737,647, filed March 27, 1947, and an application of R. C. Jones, Serial No. 741,914, filed April 16, 1947, all assigned to the Westinghouse Electric Corporation.

Heretofore, linear-motor catapults have been utilized for plane-launchings, for assisting the plane during its accelerating-run, for shortening the necessary length of the accelerating-run, thereby making it feasible for the plane to take off from a small landing-field. In general, as a practical matter, it is necessary, or highly desirable, to make it possible for the plane to land at the same field from which it takes off. Since the landing-speed is practically the same as the takeoff-speed, it will be necessary to decelerate the plane, on landing, at a fair rate, which is somewhat less than the rate at which it was accelerated during takeoff, the reduced decelerating rate being permissible because of the possibility of utilizing the entire length of the runway for the landing-operation, without the necessity for subsequently stopping and controlling a rapidly moving shuttle-car, as is necessary after a plane-launching operation.

In general, the problem of arresting motion is not as difficult as the problem of imparting motion to a heavy body, but there nevertheless remains the problem of providing a feasible means for obtaining an assisted deceleration of a plane after it has landed.

The problem of a plane-landing catapult, or a plane-landing use of a plane-launching catapult, is principally a problem of providing a suitable automatic control. An automatic controlling-means is necessary, because of the extremely high landing speeds of planes, the large masses involved, and the necessity for approximately matching the catapult-speed with the plane-speed, and causing the plane to overtake the cata-

2

pult-car at a particular instant, or at a particular point on the field, with a fair degree of accuracy. These requirements require split-second timing, which makes automatic control practically a necessity.

The general object of my invention is to provide a plane-landing catapult-assembly, with suitable automatic electrical control.

With the foregoing and other objects in view, my invention consists in the circuits, systems, operations, combinations, apparatus and parts hereinafter described and claimed, and illustrated in the accompanying drawing, wherein:

Figure 1 is a diagrammatic prospective view, not to scale, showing a portion of a landing-field equipped with my electrically controlled catapult-car for reducing the length of the landing-run of an airplane which is landing at that field, and

Fig. 2 is a simplified schematic view of circuits and apparatus illustrative of the general nature of a suitable automatic electrical control for the catapult-car, or shuttle-car, as it is commonly called.

In Fig. 1, I show a plane 1, which is about to land on a field 2 which is provided with an electrical linear-motor catapult which is represented by a shuttle-car 3, operating on a track-way-system which is diagrammatically represented by a single line 4, in Fig. 1. The shuttle-car 3 is shown as standing at its starting-point, ready for a plane-landing operation. To assist the airplane-pilot in landing, the field is marked with a landing-line 5 extending back of the starting-point of the car 3 on the trackway 4, and the field is also marked with a cross-line 6, to indicate the point where the pilot should try to touch the runway, on landing. This landing-point should be some 100 feet or 200 feet, or other suitable distance, back of the starting-point which is represented by the position of the shuttle-car 3 in Fig. 1.

At or somewhere near the landing-point, which is at the intersection of the field-markers 5 and 6, I provide a plane-detector 7, which is preferably sunk into the field, as diagrammatically indicated in Fig. 1. This plane-detector may be of any suitable type which will detect the presence or near-approach of an incoming plane. Suitable detectors for this purpose would include a proximity-fuse, which operates on the principle of radio-wave reflection, or a photoelectric cell, which operates on the principle of light-ray reflection; or the plane-detector may be any other sort of device which will operate as a switching-means.

or relay PD which will respond to the approach or passage of the incoming plane 1.

In Fig. 2, the shuttle-car 3 is represented, at the bottom of the figure, by the 3-phase primary winding of a motor M, which is spread out flat, and carried by the shuttle-car 3. The secondary winding of the motor extends along the trackway 4, and is not indicated in detail in either Fig. 1 or Fig. 2. In Fig. 2, the trackway 4 is diagrammatically shown somewhat more in detail than in Fig. 1, and it is shown as comprising a track TRK, and three motor-feeding buses B1, B2 and B3, of which the buses B2 and B3 are third-rail buses, extending along the trackway, while the bus B1 is connected, as shown, to the track TRK, by means of a plurality of feeder-connections 20, located at a plurality of spaced points 8, 10, etc., along the trackway. These feeder-connections 20 are equipped with current-transformers CT—8, CT—10, etc., which are utilized to energize either one of two track-relays Trk—1 and Trk—2, under the control of a position-selector drum 21, as more particularly described and claimed in the R. C. Jones application, Serial No. 537,515.

Only the first four positions of the distance-selector drum 21 are shown, this drum being utilized for the purpose of preselecting a particular one of the current-transformers CT to be connected to the operating-coil of one of the track-relays Trk—1 or Trk—2, and for also, as a safety-measure or backup-protection, connecting the next succeeding current-transformer CT to the actuating-coil of the other track-relay, so that it can operate in case of failure of the first one. In each position of the drum 21, all of the remaining current-transformers CT are short-circuited. These current-transformers CT become energized only when the shuttle-car is in a track-position close to the location of the feeder-connection 20 in which the particular current-transformer is located, so that the current-transformers are responsive to the position of the car on the track, during the accelerating-run of the car.

The three terminals of the primary motor-winding M of the shuttle-car 3 are at all times connected to the track TRK, the third-rail bus B2, and the third-rail bus B3, respectively, by means of current-collector shoes 22.

In Fig. 2, the power-plant is diagrammatically represented, in its barest essentials, by means of a three-phase generator AC—GEN, and a constant-voltage direct-current energy-source or sources which are schematically represented by positive and negative bus-terminals (+) and (—). The polyphase generator AC—GEN is provided with polyphase output-terminals T1, T2 and T3, and it is also provided with a field-winding 23.

The simplified schematic diagram of Fig. 2 shows eleven across-the-line circuits, numbered L1 to L11, respectively, for the various control-apparatus, all of which is shown, for the purpose of simplification, as being connected across the same direct-current bus-terminals (+) and (—).

In the diagram, the various relays or electrically operated switches or contactors, are suitably indicated by letters or legends, and these letters or legends are applied both to the operating-coils and to all of the contacts of any particular relay or switch, and in addition, arrows or dotted lines are used as a convention for symbolically tying together the various parts of any given relay or switch. The switches are all shown in their non-actuated positions.

The first line L1 of the diagram shows the use of the plane-detector make-contact PD, in series with three "break" or back-contacts 24, 25 and 26 of the two track-relays Trk—1 and Trk—2, and an auxiliary time-delay relay TX1, respectively. These four serially connected contacts PD, 24, 25 and 26 are utilized to energize a landing-initiating circuit, from the positive bus (+) to a conductor 27, which energizes the actuating-coil of a landing-control relay LC, the function of which is to initiate the energization of the automatic landing-control mechanism, and to maintain its energization until the complete sequence of a plurality of predetermined automatic operations has been carried through to completion, as will be subsequently described.

The second line L2 of the diagram shows that the actuation of the landing-control relay LC immediately closes its make-contact 28, which energizes a conductor 29 having two branch-circuits. The first branch-circuit of 29 includes the back-contacts 30 of a No. 4 auxiliary time-delay relay TX4, which is connected to the energizing-circuit 27 of the landing-control relay LC. The circuit 28—29—30 thus operates as a holding-circuit for the landing-control relay LC.

The second branch-circuit of the conductor 29 contains the three serially-connected back-contacts 31, 32 and 33, of the two track-relays Trk—1 and Trk—2 and the No. 1 auxiliary time-delay relay TX1, respectively, and these three serially connected contacts are utilized to energize a circuit 34, which continues on, through two serially connected back-contacts 35 and 36 of a braking-relay or contactor Bkg and a reverse-relay or contactor R, respectively, to energize a conductor 37 which energizes the actuating-coil of a forward-contactor F.

The forward-contactor conductor 37 has a branch-circuit containing a make-contact 38 of said forward-contactor F, which continues on, through a back-contact 39 of a field-switch Fld, and a make-contact 40 of the landing-control relay LC, to energize a conductor 41 which energizes the actuating-coil of the field-switch Fld. The field-switch conductor 41 has a branch-circuit containing a make-contact 42 of the landing-control relay LC, which is utilized to immediately energize a No. 2 field-resistance relay Fld—R2. The energization of the field-switch Fld closes its make-contact 43, which bypasses its back-contact 39, thus establishing a holding-circuit for the field-switch Fld. The make-contact 43 preferably closes before the back-contact 39 opens.

The landing-control energizing-circuit 27 has a branch-circuit 44, containing three parallel-connected make-contacts 45, 46 and 47 of the two track-switches Trk—1 and Trk—2 and the No. 1 auxiliary time-delay relay TX1, respectively, and these three contacts are utilized to energize a circuit 48 containing two serially connected back-contacts 49 and 50 of the forward-contactor F and the field-switch Fld, respectively, to energize a conductor 51 which energizes the actuating-winding of a braking-contactor Bkg. The braking-contactor circuit 51 has a branch-circuit containing a make-contact 52 of a No. 2 auxiliary time-delay relay TX2, which energizes a conductor 53 which energizes a No. 1 braking-resistance relay Bkg—R1. The conductor 53 has a branch circuit containing a back-contact 54 of a No. 3 auxiliary time-delay relay TX3, for energizing the actuating-coil of a No. 2 braking-resistor relay Bkg—R2.

5

The foregoing connections complete the main relay-coil connections for an automatic landing-operation, including an initial polyphase-power accelerating-run, under the control of the forward-contactor F' , followed by a direct-current braking-operation, under the control of the braking-contactor Bkg , the operation of which will be subsequently pointed out in detail. At the conclusion of this automatic operation, the shuttle-car 3 , or M , will be left either standing still or operating at a relatively slow speed. In either event, in order to disconnect the shuttle-car from the plane which it is assisting, it is necessary to move the shuttle-car forward again, ahead of the plane, or to make the plane drop back, for a sufficient distance to enable the pilot to turn the plane and move it off of the runway, after which the shuttle-car may be brought back, usually under manual control, to its starting-position, to get it in position for another plane-landing operation.

The third line L_3 of the schematic diagram shows a circuit containing a back-contact 55 of the landing-control relay LC , to energize a conductor 56 which is utilized for serving a spotting-switch SS , which performs the slow-return functions of the main controller-switch of the Powers patent, or the spotting-switch functions of the R. C. Jones application, Serial No. 537,515. As described and claimed in the R. C. Jones application, Serial No. 741,914, this spotting-switch SS can not be utilized except when the operation-controlling, or landing-controlling, relay LC is in its deenergized position, wherein its back-contact 55 is closed.

The spotting-switch SS has two forward-positions, designated by the suffixes F'_1 and F'_2 , and two reverse-positions, designated by the suffixes R'_1 and R'_2 , there being several switch-contacts in each of these four positions.

From the spotting-switch energizing-conductor 56 , there are four branch-circuits. A first branch-circuit includes two parallel-connected make-contacts 57 and 58 of the two forward positions $SS-F'_1$ and $SS-F'_2$ of the spotting-switch, and these two contacts are utilized to energize the circuit $34-35-36-37$ which energizes the forward-contactor F . A second branch-circuit of the conductor 56 includes two parallel-connected make-contacts 59 and 60 , which are closed in the two reverse-positions $SS-R'_1$ and $SS-R'_2$ of the spotting-switch SS , and these two contacts are utilized to energize a conductor 61 containing two serially-connected back-contacts 62 and 63 of the braking-contactor Bkg and the forward-contactor F , respectively, to energize the actuating-winding of the reverse-contactor R . A third branch-circuit of the conductor 56 includes four parallel-connected make-contacts 64 , 65 , 66 and 67 , which are closed in all four positions $SS-F'_1$, $SS-F'_2$, $SS-R'_1$ and $SS-R'_2$ of the spotting switch SS , these four contacts are utilized to energize the energizing-circuit conductor 41 of the field-switch Fld . A fourth branch-circuit of the conductor 56 includes two parallel-connected make-contacts 68 and 69 which are energized in the No. 2 forward and reverse positions $SS-F'_2$ and $SS-R'_2$ of the spotting switch SS , and these two contacts are utilized to energize a circuit 70 containing a back-contact 71 of the landing-control relay LC , to energize the actuating-coil of the No. 1 field-resistance relay $Fld-R_1$.

The fourth line L_4 of the schematic diagram shows the use of a reset-pushbutton, marked Reset- RB , in a circuit containing a serially-con-

6

nected back-contact 72 of the landing-control relay LC , to energize three reset-coils of the two track-relays $Trk-1$ and $Trk-2$, and the No. 1 auxiliary time-delay relay $TX1$. The three reset-coils are designated by the legends Reset- $Trk1$, Reset- $Trk2$ and Reset- $TX1$. These three relays $Trk-1$, $Trk-2$ and $TX1$ are position-retaining relays, which remain in their actuated positions, once they are momentarily actuated, until they are reset by a momentary energization of their respective reset-coils.

The fifth line L_5 of the schematic diagram shows the energization of an inverter 73 , which supplies alternating-current voltage, of any suitable frequency, to four alternating-current timers, or time-delay relays, $TD1$ to $TD4$, which are utilized to time the accelerating-run and the various portions of the direct-current braking-operation. The first timer $TD1$ is actuated, or set in motion, by a make-contact 74 of the forward-contactor F' , while the second, third and fourth timers $TD2$, $TD3$ and $TD4$ are respectively actuated, or set in motion, by the make-contacts 75 , 76 and 77 of the braking-contactor Bkg , a No. 2 auxiliary time-delay relay $TX2$, and a No. 3 auxiliary time-delay relay $TX3$, respectively.

The sixth line L_6 of the diagram shows that the first timer $TD1$ has a make-contact 78 which energizes the No. 1 auxiliary time-delay relay $TX1$, this relay being a position-retaining relay, as previously explained.

The lines L_7 , L_8 and L_9 of the schematic diagram show the use of three parallel-connected make-contacts 79 , 80 and 81 of the two track-relays $Trk-1$ and $Trk-2$ and the No. 1 auxiliary time-delay relay $TX1$, to energize a circuit $81A$, having several branch-circuits, which energize the actuating-coils of the No. 2, No. 3 and No. 4 auxiliary time-delay relays $TX2$, $TX3$ and $TX4$, respectively, through the respective make-contacts 82 , 83 and 84 of the correspondingly numbered timers $TD2$, $TD3$ and $TD4$, each controlling its own auxiliary time-delay relay. Each of these auxiliary time-delay relays $TX2$, $TX3$ and $TX4$, whenever energized, immediately seals itself in, through a make-contact $82'$, $83'$ or $84'$, as the case may be, bypassing the corresponding timer-contacts 82 , 83 and 84 , respectively.

The tenth line L_{10} of the schematic diagram shows the use of two make-contacts 85 and 86 of the field-switch Fld for energizing the field-winding 23 of the alternating-current generator AC-GEN, across the direct-current terminals (+) and (-), through a field-resistance 87 , various portions of which are short-circuited by the make-contacts 88 and 89 of the respective field-resistance relays $Fld-R_1$ and $Fld-R_2$. The generator field winding 23 is preferably bypassed by a field-discharging resistor 90 .

The eleventh line L_{11} of the schematic diagram shows how the make-contacts 91 and 92 of the braking-contactor Bkg connect two of the track-system buses B_1 and B_3 , respectively, to the positive and negative terminals (+) and (-), respectively, through a current-limiting braking-resistance 93 and a choke-coil 94 . Various portions of the braking-resistance 93 are short-circuited by the make-contacts 95 and 96 of the respective braking-resistance relays $Bkg-R_1$ and $Bkg-R_2$, thus controlling the amount of braking-energy. The choke-coil 94 serves to limit the rate of rise of the direct-current in the braking-circuit, when the braking-contactor Bkg is closed,

thus protecting the direct-current bus (+) and (-) from having too sudden a load thrust upon it.

The switching equipment of my automatic control-system is completed by the main contacts 97 and 98 of the polyphase contactors F and R, which apply the polyphase power of the generator-terminals T1, T2 and T3 to the motor-circuit buses B1, B2 and B3, in either the forward or reverse phase-sequence, respectively.

As shown in Fig. 1, suitable shock-absorbing engagement-means or coupling-means are provided, for cushioning the overtaking-contact of the plane with the accelerated car on the landing-field. This coupling-means may take any one of a number of different forms, and is diagrammatically indicated as including a depending hook 100, in the rear portion of the underside of the plane 1. When the plane overtakes the shuttle-car 3, the hook 100 engages a transverse cable 101, which extends between pulleys 102 on the car, the ends of the cable being anchored in oleo shock-absorbers 103, which may yield a number of feet in length, while enabling the plane and the car to adjust themselves for any small initial difference in their speeds at the moment of contact. This shock-absorbing plane-engaging means may be arranged, if desired, for quick installation and removal on the shuttle-car 3. It will be understood that the transverse bight-portion of the cable 101 will be disposed about one or two feet, or other suitable distance, above the top of the shuttle-car 3.

In the operation of my invention, when a plane is about to come in, to the landing-field 2, for an assisted landing, the operator in the power-plant will be given advance-notice of the landing-speed of the plane, and he will set up the controls, accordingly, so as to apply the correct amount of power, or the full power, to the shuttle-car motor M, for the correct length of time, or for the correct distance along the trackway 4, to accelerate the car to a speed a little less than the speed of the plane which is about to land. The timing should be such that the plane will overtake the shuttle-car at about the instant when the accelerating power is cut off, or a second or so, or a fraction of a second, thereafter.

The power-plant operator makes these adjustments with the aid of charts or tables (not shown) which enable him to set the distance-selector drum 21 so as to cut off the power when the car reaches the proper point along the trackway. This distance-selecting adjustment, for presetting the length of the accelerating-run of the shuttle-car, can be utilized, either with full power-application to the shuttle-car, or in conjunction with any one of several charted adjustments of the amount of field-resistance 87 which is cut out by the No. 2 field-resistance relay Fld-R2, as indicated at 104 in line L10 of Fig. 2. As a backup protective-means, the power-plant operator also sets or adjusts the timing of the No. 1 timer Td1, to cut off the accelerating-power, at a time, as shown on his charts, such that the attained car-speed would be only very slightly larger than if the accelerating-run had been terminated by one of the track-relays Trk-1 or Trk-2 which are associated with the distance-selector drum 21. This affords protection, even though the track-relays should both fail.

If there is a wide margin of difference in the weights of the various planes which come in to the field for assisted landings, the power-plant operator may also secure advance information

of the weight of the incoming plane, by which he may adjust or preselect the time-settings of the three braking-controlling timers TD2, TD3 and TD4, or he may preselect the final amount of the braking-energy, in the third or final stage of the braking-operation, by adjusting the amount of the braking-resistance 93 which is cut out by the No. 1 braking-resistance relay Bkg-R1, as indicated at 105 in line L11 of Fig. 2.

10 The initial power-plant presettings or adjustments, in readiness for an incoming plane, will be better understood when the sequence of the landing-operation has been traced to its conclusion, as will now be done.

15 The pilot of the incoming plane will line up along the continuous straight line 5-4 on the landing-field 2, and will try to touch the runway approximately on the spot indicated by the cross-line marker 6 on the runway.

20 Approximately at the instant when the plane makes landing-contact with the field, the plane-detector 7 responds, and closes its PD contact in the first line, L1, of the schematic control-diagram. This operation automatically sets in

25 operation a complete sequence of electrical control-functions which perform a predetermined sequence of control-operations, and carry them through to completion, without the control of the operator, other than the set of pre-setting adjustments such as those which have already been described, or any other set of presetting control-adjustments which may be desirable.

30 The momentary closing of the plane-detector contact PD, in line L1 of Fig. 2, energizes the operation-controlling or landing-controlling relay LC, which immediately locks itself in, through a holding-circuit 28-29-30-21, which remains closed until the complete landing-operation has been finished, as indicated, in the illustrated form of embodiment, by the opening of the back-contact 30 of the last auxiliary time-delay relay TX4.

35 The actuation of the landing-control relay LC immediately energizes the forward-contactor F, through the circuit from 29 through 31 to 37; and the completion of the response of the forward contactor F immediately energizes the field-switch Fld, through the circuit from 37 to 38 through 41; and at the same time, the No. 2 field-

40 resistance relay Fld-R2 is energized through the circuit 41-42. These operations cause the polyphase generator AC-GEN to be connected to the car-serving buses B1, B2 and B3, through the forward-phase-sequence contactor-contacts 97, at a time when the generator is unexcited, and hence when its voltage is very low. Immediately, however, exciting-energy is applied to the generator field-winding 23, and the field-flux begins to build up, in the generator, at a rate which is determined by the time-constant of the generator,

45 and by the voltage and resistance-conditions of the field-energizing circuit which is line L10 of the schematic diagram. The generator-field, and hence the generator-voltage, thus builds up

50 smoothly, but rapidly, so as to apply the accelerating-power to the shuttle-car 3 or M, without too great shock on the power-plant or the forward-contactor F. Before the car has moved very many feet, the full power (or any other preselected power) of the generator AC-GEN will be applied to the car.

55 The accelerating-run of the shuttle-car is normally interrupted by the operation of one of the track-relays Trk-1 or Trk-2, which opens its back-contact 31 or 32, as the case may be, in

the energizing-circuit of the forward contactor F and the field-switch Fld. At the same time, the track-relay closes its make-contact 45 or 46 in the energizing-circuit 44-51 of the braking-contactor Bkg, and as soon as the forward-contactor F and the field-switch Fld are fully opened, their back-contacts 49 and 50 will complete this energizing-circuit for the braking-contactor Bkg.

While I have shown the three parallel-connected make-contacts 45, 46 and 47 as automatic-relay contacts, of the relays Trk-1, Trk-2 and TX1, for energizing the braking-contactor Bkg and initiating the braking-operation of the shuttle-car, I wish it to be understood that I am not limited to these precise contacts or relay-means; as the braking-operation could be initiated either manually, or by any other automatically responding control-means. The essential thing is that the braking-operation should be initiated, manually or automatically, either just as the plane is approaching toward its overtaking-contact with the shuttle-car, or as soon after such contact as is reasonably convenient. The contact-making act, between the plane and the car, may be visually observed by an operator or by a light-sensitive relay (not shown) placed to one side of the runway, or said act may be responded to by signalling apparatus (not shown) on the plane or the car, and the signal may be responded to, by the power-plant control-operator, either manually or automatically. I wish my braking-initiating contacts, such as 45, 46, 47, to be understood, therefore, as being symbolically representative, in their broader aspects, of any equivalent braking-initiating switching-means.

While I have chosen for illustration, an exemplary automatic control-sequence in which the braking-power is applied immediately upon the discontinuance of the accelerating-power, it should be understood that my invention is not limited to this immediate application of the braking-power, immediately after the discontinuance of the full accelerating-power, but a time-delay interval may be interposed, either by completely cutting off the forward accelerating-power, waiting an interval, and then completely applying the full braking-power, or by first reducing the accelerating-power to a very small amount, before finally cutting off the accelerating-power and then instantly applying the braking-power, or by suddenly cutting off the full accelerating-power, and instantly applying a very small braking-power, which is left on for a predetermined time-interval, before applying the full braking-power. I have chosen to illustrate the third alternative, under the control of the No. 2 timer TD2, and this illustration is intended to be representative of any suitable means for introducing a time-interval, according to the time-setting of the No. 2 timer TD2, during which the speed of the shuttle-car is not changing very greatly, either by way of acceleration or deceleration. This expedient is desirable, in order to provide a certain factor of safety in regard to the predetermination of the precise point in the landing field, or the precise instant of time, at which the plane 1 overhauls the shuttle-car 3.

In the form of embodiment which I now prefer, as shown in Fig. 2, the energization of the braking-contactor circuit 44-51 applies direct-current braking-power to the shuttle-car, with the full amount of the braking-resistance 93 in circuit, as shown in the line L11 of the schematic diagram. The value of this braking-resistance

93 may be such that the braking-power which is applied to the shuttle-car during this portion of the operating-sequence is very small, merely enough to help to hold the contacting-cable 101 taut, when the plane hook 100 first engages the same.

Here again, the apparatus which I have chosen for illustration is intended to be symbolic, in a broader sense, of any suitable or equivalent means for performing a braking or decelerating function, by means of any suitable electrical energization of the shuttle-car which will result in reducing its speed. Such braking-energization of the shuttle-car would include, in its broadest range of equivalents, the application of reverse-phase-sequence polyphase power, for plug-reversal, as in the Powers patent, or the application (as shown) of direct-current power to two or more of the phases or phase-terminals of the polyphase shuttle-car motor M.

After the expiration of the time-setting of the No. 2 timer TD2, the No. 2 auxiliary time-delay relay TX2 is energized, and closes its make-contact 52 in the energizing-circuit 51-52-53 of the two braking-resistance relays Bkg-R1 and Bkg-R2, thus cutting out nearly all of the braking-resistance 93, and applying the full amount of braking-power which the apparatus will safely stand, or any other desired amount of braking-power.

After a predetermined time-interval, after the energization of the No. 2 auxiliary time-delay relay TX2, the No. 3 timer TD3 closes its contact 83 and energizes the No. 3 auxiliary time-delay relay TX3 which immediately opens its back-contact 54 and deenergizes the No. 2 braking-resistor relay Bkg-R2. The opening of the relay Bkg-R2 puts back, in the braking-circuit L11, some of the braking-resistance 93. This operation should preferably be timed so as to occur at some time when the speed of the shuttle-car, and hence the speed of the plane, has been reduced to some small amount, but has not been brought to standstill.

The amount of braking-energy which is thus finally applied to the car, after the operation of the No. 3 timer TD3, will thus be reduced, so as to lessen the jerk with which the car might otherwise be stopped, as will be readily understood. While only a single stage of brake-reducing power is shown, it will be readily understood that a multiplicity of such stages might be utilized, if desired. The problem of smooth-stopping may not make it necessary to utilize more than one, if any, brake-reducing stage, because of the fact that the effectiveness of the direct-current energization of some or all of the polyphase windings of a squirrel-cage motor is a function of the speed of the motor, so that the braking-pull or force inherently falls off rapidly when the speed of the shuttle-car is reduced, even without any reduction in the direct-current braking-energy, as by the opening of the No. 2 braking-resistance relay Bkg-R2.

However, even though the resistance-introducing step corresponding to the opening of the TX3 back-contact 54 is not needed from the standpoint of securing a smooth stopping, without any final jerk, because of the inherent falling-off of the braking-force as the motor-speed approaches zero, the resistance-introducing step 54, or equivalent means for reducing the applied direct-current braking-energy, may frequently be necessary because of the increased magnetic flux which a given braking-current produces as the shuttle-

11

car (and its motor) approaches standstill. When an induction-motor is moving at a reasonable speed, while its primary winding M is excited with a direct current, the unidirectional flux, in the primary winding, cuts the squirrel-cage (or other) secondary winding (in this case stretched out along the trackway), so that the induced circulating current, in the secondary winding, bucks down the primary-winding flux. When the motor stops, or nearly stops, the primary-winding flux reaches its full magnitude. Now, in an ordinary circular motor, this phenomenon would not be very important, but in a linear motor, as in my catapult, the magnetic flux produces a very considerable magnetic pull between the shuttle-car 3 and the track-structure 4. The necessity for keeping down the final amount of flux, which appears when the motor (or shuttle-car) approaches standstill, so as to limit the mechanical bending of either the car or the trackway, imposes a definite limit on the amount of braking-current which may be permitted to flow in the primary winding M when the shuttle-car speed is reduced to zero. Hence, the employment of the resistance-introducing step corresponding to the opening of the TX_3 back-contact 54 before the car-speed is reduced to too low a value, makes it possible to use more braking-power while the car is in fast motion, without mechanically overstressing either the car or the trackway.

After a predetermined time-interval after the actuation of the resistance-introducing step 54 by the energization of the No. 3 auxiliary time-delay relay TX_3 , the last timer TD_4 operates, energizing the No. 4 auxiliary time-delay relay TX_4 , and causing it to open its back-contact 30 in the holding-circuit of the landing-control relay LC , and at the same time deenergizing the braking-contactor energizing-circuit 44-51.

This No. 4 time-delay setting would usually preferably be set so that the shuttle-car (and the plane) will have been brought to standstill, with an additional time added, for a reasonable factor of safety, before the braking-circuit L_{11} is deenergized, thus finally relieving the power-plant of an unnecessary power-drainage, relieving the shuttle-car motor-winding M of unnecessary overheating and releasing the shuttle-car in readiness for further polyphase energization and control, as will be subsequently described.

However, as previously intimated, it is possible to operate my system so that No. 4 timer TD_4 interrupts the direct-current braking-circuit before the car and the plane have come to a full stop, being merely reduced to a reasonably slow and readily controllable speed, after which the car would be left to run ahead, either coasting without polyphase propelling-power, or with the application of a small amount of forward phase-sequence polyphase-power, either manually or automatically applied, while the pilot of the plane would apply his own brakes and cause the plane to detach itself from the shuttle-car coupling-cable 101, after which the pilot could turn the plane and move it off of the runway in the ordinary manner. The shuttle-car could then be brought to dead standstill, either automatically or by manual control by the use of the spotting-switch SS .

After the shuttle-car has been brought to standstill, by whatever braking-power means is utilized, the car can then be controlled by the spotting-switch SS , by means of which the operator can move the car either forward or backward, with either one of two different amounts of polyphase

12

voltage, according as the first or second spotting-switch position is utilized, in either the forward or reverse direction. By this means, the shuttle-car can be disengaged from the plane-hook 100 (if it is not already disengaged), and after the plane has moved itself off of the runway, the shuttle-car can be returned to its starting-point, and accurately "spotted" in position in readiness for another landing-operation, with another plane.

At some time after the completion of the automatic landing-operation just described, and before the next automatic landing-operation, it is necessary to reset the position-retaining relays 15 $Trk-1$, $Trk-2$ and TX_1 , by a momentary energization of the reset-pushbutton $Reset-PB$, in line L_4 of the schematic diagram.

While, in the foregoing explanation, I have described only the plane-landing functions of a catapult, and while I have shown only the plane-landing control in the drawing, it is to be understood that the same shuttle-car, track, and power-plant may be used also for plane-launchings, with suitable modifications in the control-circuits and the coupling-attachments.

While I have illustrated my invention in an exemplary, and at present preferred, form of embodiment, I wish it to be understood that my invention is of rather broad application, representing broadly new principles of operation and control, and I desire that the appended claims shall be understood as embracing a suitable range of equivalents in regard to the precise means and operations which are employed.

I claim as my invention:

1. A plane-landing catapult-assembly for reducing the length of the landing-run of an airplane which is landing at a landing-field, said catapult-assembly comprising: a self-propelled, electrically energized car, initially standing at a predetermined starting-point in the field; accelerating-means, including an electrical energy-source and control-means, for providing an automatically controlled electrical accelerating-energization for the car; means for presetting the accelerating-operation; decelerating-means, including an electrical energy-source and control-means, for providing an electrical decelerating-energization for the car; plane-detecting means, back of said starting-point in the field, for detecting the landing-approach of a plane at a predetermined detection-point back of said starting-point; means responsive to said plane-detecting means for automatically initiating said accelerating-operation; shock-absorbing coupling-means for cushioning the overtaking-contact of the plane with the accelerated car on the landing-field; and means for initiating the decelerating-operation.

2. A plane-landing catapult-assembly for reducing the length of the landing-run of an airplane which is landing at a landing-field, said catapult-assembly comprising: a self-propelled, electrically energized car, initially standing at a predetermined starting-point in the field; accelerating-means, including an electrical energy-source and control-means, for providing an automatically controlled electrical accelerating-energization for the car; means for presetting the accelerating-operation; decelerating-means, including an electrical energy-source and control-means, for providing an automatically controlled electrical decelerating-energization for the car; means for presetting the decelerating-operation;

3. A plane-landing catapult-assembly for reducing the length of the landing-run of an airplane which is landing at a landing-field, said catapult-assembly comprising: a self-propelled, electrically energized car, initially standing at a predetermined starting-point in the field; accelerating-means, including an electrical energy-source and control-means, for providing an automatically controlled electrical accelerating-energization for the car; means for presetting the accelerating-operation; decelerating-means, including an electrical energy-source and control-means, for providing an automatically controlled electrical decelerating-energization for the car; means for presetting the decelerating-operation; plane-detecting means, back of said starting-point in the field, for detecting the landing-approach of a plane at a predetermined detection-point back of said starting-point; means responsive to said plane-detecting means for automatically initiating said accelerating-operation; shock-absorbing coupling-means for cushioning the overtaking-contact of the plane with the accelerated car on the landing-field; and means for initiating the decelerating-operation.

point in the field, for detecting the landing-approach of a plane at a predetermined detection-point back of said starting-point; means responsive to said plane-detecting means for automatically initiating said accelerating-operation; shock-absorbing coupling-means for cushioning the overtaking-contact of the plane with the accelerated car on the landing-field; and means for initiating the decelerating-operation.

3. The invention as defined in claim 1, in combination with supplementary control-means for subsequently electrically energizing the car to return the car to a desired starting-point ready for another plane-landing operation.

4. The invention as defined in claim 2, in combination with supplementary control-means for subsequently electrically energizing the car to return the car to a desired starting-point ready for another plane-landing operation.

5. A plane-landing catapult-assembly for reducing the length of the landing-run of an airplane which is landing at a landing-field, said catapult-assembly comprising: a self-propelled, electrically energized car, initially standing at a predetermined starting-point in the field; accelerating means, including an electrical energy-source and control-means, for providing an automatically controlled electrical accelerating-energization for the car; means for presetting the accelerating-operation; decelerating-means, including an electrical energy-source and control-means, for providing an automatically controlled electrical decelerating-energization for the car; means for presetting the decelerating-operation; plane-detecting means, back of said starting point in the field, for detecting the landing-approach of a plane at a predetermined detection-point back of said starting-point; means responsive to said plane-detecting means for automatically initiating said accelerating-operation; shock-absorbing coupling-means for cushioning the overtaking-contact of the plane with the accelerated car on the landing-field; and means responsive to the termination of the accelerating-operation for automatically initiating the decelerating-operation.

6. The invention as defined in claim 5, in combination with supplementary control-means for subsequently electrically energizing the car to return the car to a desired starting-point ready for another plane-landing operation.

7. A plane-landing catapult-assembly for reducing the length of the landing-run of an airplane which is landing at a landing-field, said catapult-assembly comprising: a polyphase-motored shuttle-car, initially standing at a predetermined starting-point in the field; a trackway for said shuttle-car in the landing-field; a polyphase motor-energizing bus-system which is continuously connected to said polyphase-motored shuttle-car; accelerating-means, including a polyphase energy-source and control-means, for providing an automatically controlled electrical accelerating-energization for the motor-energizing bus-system; means for presetting the accelerating-operation of the shuttle-car; decelerating-means, including an electrical energy-source and control-means, for providing an electrical decelerating-energization for the motor-energizing bus-system; plane-detecting means, back of said starting-point in the field, for detecting the landing-approach of a plane at a predetermined detection-point back of said starting-point; means responsive to said plane-detecting

means for automatically initiating said accelerating-operation; shock-absorbing coupling-means for cushioning the overtaking-contact of the plane with the accelerated car on the landing-field; and means for initiating the decelerating-operation.

8. The invention as defined in claim 7, in combination with supplementary control-means for subsequently electrically energizing the car to return the car to a desired starting-point ready for another plane-landing operation.

9. A plane-landing catapult-assembly for reducing the length of the landing-run of an airplane which is landing at a landing-field, said catapult-assembly comprising: a polyphase-motored shuttle-car, initially standing at a predetermined starting-point in the field; a trackway for said shuttle-car in the landing-field; a polyphase motor-energizing bus-system which is continuously connected to said polyphase-motored shuttle-car; accelerating-means, including a polyphase energy-source and control-means, for providing an automatically controlled electrical accelerating-energization for the motor-energizing bus-system; means for presetting the accelerating-operation of the shuttle-car; decelerating-means, including an electrical energy-source and control-means, for providing an automatically controlled electrical decelerating-energization for the motor-energizing bus-system; means for presetting the decelerating-operation of the shuttle-car; plane-detecting means, back of said starting-point in the field, for detecting the landing-approach of a plane at a predetermined detection-point back of said starting-point; means responsive to said plane-detecting means for automatically initiating said accelerating-operation; shock-absorbing coupling-means for cushioning the overtaking-contact of the plane with the accelerated car on the landing-field; and means for initiating the decelerating-operation.

10. The invention as defined in claim 9, in combination with supplementary control-means for subsequently electrically energizing the car to return the car to a desired starting-point ready for another plane-landing operation.

11. A plane-landing catapult-assembly for reducing the length of the landing-run of an airplane which is landing at a landing-field, said catapult-assembly comprising: a polyphase-motored shuttle-car, initially standing at a predetermined starting-point in the field; a trackway for said shuttle-car in the landing-field; a polyphase motor-energizing bus-system which is continuously connected to said polyphase-motored shuttle-car; accelerating-means, including a polyphase energy-source and control-means, for providing an automatically controlled electrical accelerating-energization for the motor-energizing bus-system; means for presetting the accelerating-operation of the shuttle-car; decelerating-means, including an electrical energy-source and control-means, for providing an automatically controlled electrical decelerating-energization for the motor-energizing bus-system; means for presetting the decelerating-operation of the shuttle-car; plane-detecting means, back of said starting-point in the field, for detecting the landing-approach of a plane at a predetermined detection-point back of said starting-point; means responsive to said plane-detecting means for automatically initiating said accelerating-operation; shock-absorbing coupling-means for cushioning the overtaking-contact of the plane with the accelerated car on the landing-field; and

means responsive to the termination of the accelerating-operation for automatically initiating the decelerating-operation.

12. The invention as defined in claim 11, in combination with supplementary control-means for subsequently electrically energizing the car to return the car to a desired starting-point ready for another plane-landing operation.

13. In combination, a polyphase load-circuit supply-line, a polyphase energy-circuit supply-line, a direct-current energy-circuit supply-line, a polyphase motor constantly connected to said polyphase load-circuit supply-line, alternating-current-controlling means operable only when said direct-current energy-circuit supply-line is disconnected and comprising a main starting-contactor for energizing said polyphase load-circuit supply-line from said polyphase energy-circuit supply-line in the one phase-sequence or the other for a forward run of said polyphase motor, means for opening said main starting-contactor for terminating said forward run, direct-current-controlling means operable only when said polyphase energy-circuit supply-line is disconnected and comprising a braking-contactor for energiz-

ing a plurality of conductors of said polyphase load-circuit supply-line from said direct-current energy-circuit supply-line for braking said polyphase motor, timing-means actuated at the commencement of the braking-operation, means for presetting the timing-means, means responsive to said timing-means for reducing the direct-current braking-energy applied to the polyphase motor, and means for subsequently opening said braking-contactor for terminating the direct-current braking.
